Int. Cl. D21—04

U.S. Cl. D34—5

FIG. 1 is a perspective view of an intentional-impact rebounding amusement vehicle showing our new design;
FIG. 2 is a top plan view thereof on a slightly smaller scale;

FIG. 3 is a bottom plan view thereof on the same scale as FIG. 2; and

FIG. 4 is a side elevation thereof on a larger scale than FIGS. 2 and 3, the side opposite being a mirror image of the side shown.

We claim:

The ornamental design for an intentional-impact rebounding amusement vehicle, substantially as shown and described.
